UNITED STATES PATENT OFFICE.

JAMES G. SUMMERS, OF CHARLESTON, WEST VIRGINIA.

STAMP-MOISTENER.

972,661.

Specification of Letters Patent. Patented Oct. 11, 1910.

Application filed July 5, 1910. Serial No. 570,279.

To all whom it may concern:

Be it known that I, JAMES G. SUMMERS, a citizen of the United States, and a resident of Charleston, in the county of Kanawha and State of West Virginia, have invented 5 certain new and useful Improvements in Stamp-Moisteners, of which the following is a specification.

This invention is an improvement in 10 stamp moisteners and has for an object to provide a novel construction of moistener which can be placed on a desk or other support and will include a sponge cup, a cup holder and a main casing so constructed as 15 to permit the easy refilling of the moistener with water, and the automatic or self-feeding of the water to the sponge and which will always be ready for convenient use; and the invention consists in certain novel 20 constructions and combinations of parts as will be hereinafter described and claimed.

In the drawing Figure 1 is a perspective view and Fig. 2 is a vertical longitudinal section of a moistener embodying my invention. Fig. 3 is a detail perspective view of 25 the main casing. Fig. 4 is a detail sectional view of the cup holder. Fig. 5 is a detail sectional view of the sponge cup with the sponge in place.

30 The device, as shown, comprises a main casing A, a cup holder B and a sponge cup C. The main casing A has a cylindrical body A' open at the top and closed at its lower end by the bottom plate A². The 35 cup holder B has a body portion B' open at the top and provided at its top or upper end with an annular outwardly projecting flange B² which rests upon the upper open end of the main casing and has a lip B³ depending 40 along the outer side of the body A' of the main casing and steadyng the cup holder firmly in position within the main casing, as best shown in Fig. 2 of the drawing.

The body B' is smaller than the body A' 45 affording a water space D between the body A' and the body B' and surrounding the latter, as will be understood from Fig. 2. The body B' is also of a length less than the body A' so that the lower end of the body B' will lie above the bottom A² of the main casing so water can circulate from the space D below the body B' to supply water to the sponge, as presently described. Near its lower end the body B' has a foraminous 50 diaphragm B⁴ which may be of a fine mesh wire cloth of brass or the like held within

the lower end of the body B' by a ring B⁵, see Fig. 4, which may be soldered or brazed in position and will operate to hold the diaphragm B⁴ firmly in place slightly above 60 the lower end of the body B' of the cup holder.

The sponge cup C has a body portion C' adapted to fit within the body B' of the cup holder and this body B' is open at the bottom and is closed at the top by a foraminous diaphragm C² which like the diaphragm B⁴ may be of a fine mesh wire cloth suitably held in the upper end of the body C' and flush with or slightly above the upper end 70 of the body C', which body C' lies approximately in the plane of the upper face of the flange B² of the cup holder. The sponge E in the cup holder rests at its lower end upon the diaphragm B⁴ and at its upper edge 75 against the underside of the diaphragm C² and when the moistener is applied to the casing it will be fed up through the diaphragm B⁴ to the sponge and thence to position to supply moisture to a stamp when the 80 latter is pressed against the diaphragm C².

In practice the moistener may be made of any suitable material, glass, metal or other substance, being employed in making the main casing, cup holder and the body 85 of the sponge cup and any suitable foraminous material such as wire cloth as above described or other fabric may be employed in the production of the diaphragms for use as described. 90

I claim:

1. A stamp moistener, substantially as herein described, comprising a main casing having a cylindrical body open at the top, a cup holder having a body portion fitting in that of the main casing and spaced from the main casing, a foraminous diaphragm at the lower end of the body of the cup holder, a lateral flange at the upper end of the body of the cup holder and extending 100 over and resting upon the upper end of the main casing and having a lip depending along the outer side of the main casing and a sponge cup fitting in the cup holder and open at its bottom and having a foraminous diaphragm at its upper end, all substantially 105 as and for the purposes set forth.

2. A stamp moistener comprising a casing open at the top, a cup holder fitting therein and having its lower end spaced from the 110 bottom of the casing and its upper end open and a sponge cup fitting in the open upper

end of the cup holder and having its lower end open and provided at its upper end with a foraminous diaphragm, substantially as set forth.

5 3. A stamp moistener comprising a casing open at the top, a cup holder having a body portion communicating at its lower end with the casing and open at its upper end and

provided at such end with a lateral flange resting upon the upper end of the casing, 10 and a sponge cup in said holder, substantially as set forth.

JAMES G. SUMMERS.
